UNITED STATES PATENT OFFICE

CHARLES H. KENNEDY, OF SWAMPSOFT, MASSACHUSETTS, ASSIGNOR TO WALTER M. LOWNEY COMPANY, OF BOSTON, MASSACHUSETTS, A CORPORATION OF MASSACHUSETTS

CONVERTIBLE BOX

Application filed November 1, 1930. Serial No. 492,721.

The object of the invention is to provide a box in which goods may be shipped and the box afterward converted into an easel in which the goods may be displayed and from 5 which they may be dispensed.

The invention can best be seen and understood by reference to the drawing in which—

Figure 1 is a front elevation of the convertible box.

Fig. 2 is a perspective of the easel into which the box is converted.

Fig. 3 is a vertical cross section of the box shown in Fig. 1, and

Fig. 4 is a plan of the member in blank 15 used in the formation of both the box and the easel, and to which member special reference will afterward be made.

Referring to the drawing:

1 represents a base-forming body. This 20 body is made of cardboard generally rectangular in form and of considerable depth with an open top, sides 2, 2', ends 3, 3' and a bottom 4. Mounted in the body to stand in an upright position therein and rising above 25 the top edge of the body is a card 5 generally rectangular in form. Extending from each of the opposite sides of the card are a set of foldable wings 9 and 10, respectively, and from the opposite ends of the card wings 11 30 and 12, respectively. All the wings are made foldable by scores 13 in the material, while the wings 9 and 10 of each set are separated by a cut 14 in the material.

The box is formed as follows:

The card 5 together with its wings is made 35 to bear a determinate relation to the body 1. The card is adapted to stand within the body in an upright position with the lower part of the card parallel with and bearing against the side 2 of the body, while the upper part of the card will extend well above the side 2 and entire top edge of the body. The card is maintained in its upright position by the wings 10, 10 turned to lie parallel with and 40 engaging the sides 3, 3' of the body 1, and by the wing 11 turned to lie parallel with and engaging the bottom 4 of the body. With the card being thus maintained to occupy an upright position in the body 1 in upright 45 extension thereof, the arrangement is pref-

erably such that the cuts 14 between the respective sets of wings 9 and 10 will then be disposed to lie below the top edge of the body. The wings 9, 9 will have been turned to lie in the same plane with the wings 10, 10, the lower edge portions of the wings 9, 9 lying parallel with and engaging the ends of the body, while the upper portions of the wings 9, 9 will rise above said ends and, like the card 5, extend well above 50 the top edge of the body. The wing 12 on the card will have been turned into a position where it will lie substantially parallel with the bottom 4 of the body and the wing 11 55 of the card bearing against said bottom. Thus mounted the winged card co-operates with the body to form an elongated container for the goods which container rises well above the top edge of the body 1 in extension thereof. A cover 15 is applied to fit telescopically 60 over that portion of the container which rises above the top edge of the body 1 and which forms an elongated neck to the body for receiving the cover, the preferred arrangement being such that when the cover is in place its bottom edge will bear against the top edge of the body 1 without telescopic extension over the body substantially as shown in Fig. 2.

The box having thus been formed is convertible into a display easel in which goods contained in the body 1 may be displayed and from which they may be dispensed. Such conversion of the box is first obtained by removing the cover 15, then raising the card 5 until the cuts 14 between the sets of wings 9 65 and 10 will lie in the same plane with the top edge of the body or above this edge. Thereupon the wings 9, 9 and wing 12 may be turned out for display purposes so that they will occupy positions substantially in the same plane with the card 5. In other words, the card 5 will then form the back of the easel with the wings 9, 9 and wing 12 extending therefrom. The card 5 then forming the back of the easel will continue to be maintained in an upright position by the body 1 acting as a base of support therefor and in which the card 5 continues to be held in place by the engagement of its wings 10, 10 and 11 with the body forming base as aforesaid.

During the time that the box is being converted into a display easel the goods contained within the body 1 will remain therein, the goods usually being arranged to stand on end in an upright position in the body 1 then forming the base of the easel, where they may be displayed on the easel and dispensed from it.

Having thus fully described my invention, 10 I claim and desire to secure by Letters Patent of the United States:—

1. A convertible box comprising a base-forming body having an open top with closed-in sides, ends and a bottom; a card mounted in said body in an upright position and rising above the top edge of said body; foldable wings on said card, certain of said wings co-operating with said body to maintain the card in an upright position as aforesaid, and other 20 of said wings co-operating with said card when the wings are folded, to form a container in elongated extension of said body, and, when the wings are open, a display easel for goods contained in said body then forming 25 the base of said easel; and a cover for said container when said wings are folded as aforesaid.

2. A convertible box comprising a base-forming body having an open top with closed-in sides, ends and a bottom; a card mounted in said body in an upright position and rising above the top edge of said body; foldable wings on said card including sets of wings on the sides of said card with a cut between the 35 wings of each set, those wings of each set lying below said cuts co-operating with said body to maintain said card in an upright position as aforesaid, and those wings lying above said cuts co-operating with said card when the 40 wings are folded to form a container in elongated extension of said body or, when the wings are open, a display easel for goods contained within said body then forming the base of said easel; and a cover for said container 45 when the wings lying above said cuts are folded as aforesaid.

3. A convertible box comprising a base-forming body having an open top with closed-in sides, ends and bottom; a card slidably mounted in said body to occupy an upright position and rising above the top edge of said body; foldable wings on said card including sets of wings on the sides of said card with a cut between the wings of each set, said cuts 55 between the respective sets of wings lying either above or below the top edge of said body as the card is slidably moved with relation to said body, those wings of each set lying below said cuts co-operating with said body 60 to maintain said card in an upright position as aforesaid, and those wings lying above said cuts co-operating with said body and card, when said cuts are arranged to lie below the top edge of said body and the wings folded, to 65 form a container in elongated extension of

said body, or, when said cuts arranged above the top edge of said body and the wings are open, a display easel for goods contained within said body then forming the base of said easel; and a cover for said container when the wings lying above said cuts are folded as aforesaid.

CHARLES H. KENNEDY.
